UNITED STATES PATENT OFFICE.

GEORGE B. WEAST, OF NEWVILLE, PENNSYLVANIA.

SHEET-METAL ROOF.

SPECIFICATION forming part of Letters Patent No. 329,789, dated November 3, 1885.

Application filed December 18, 1884. Serial No. 150,649. (No model.)

To all whom it may concern:

Be it known that I, GEORGE B. WEAST, residing at Newville, in the county of Cumberland and State of Pennsylvania, have invented 5 a Sheet-Metal Roof, of which the following is a specification.

The invention will first be described in connection with the drawings, and then pointed out in the claim.

10 Figure 1 of the drawings is a view showing my invention as applied. Fig. 2 is a cross-section through line $x-x$ of Fig. 1. Fig. 3 is a plan view of the shingle, showing its construction on the upper face. Fig. 4 is a transverse 15 section of the roof and cap.

In the drawings, A represents my metallic shingle made of sheet-tin, and B is a sheathing or roof-frame, to the transverse pieces b of which the shingles are nailed at diagonally 20 opposite corners.

I preferably make my shingle in an approximately rectangular form, although the shape may be greatly varied without departing from the principle of my invention.

25 A represents the roof-cap. It will thus be perceived that the fastening-nails are in a diagonal line at right angles to the pitch or inclination of the roof, while the complementary angles of the rectangle will be bisected by a 30 line drawn in the same direction as the pitch.

In this line of bisection I make the groove a, and on each side thereof the branch grooves a', inclined thereto and terminating therein.

By this construction a series of water-channels are provided, so as to gather the water and 35 guide it off the shingle and finally into the eaves-trough. I prefer to make these grooves a a' by corrugating the metal, so as to make them more rigid and less liable to be bent by wind or other force. On two opposite sides 40 of the shingle I make the subjacent folds a a', and on the other two sides the superposed folds a a', said folds a a' forming hooks which interlock and unify the roof, as if all its parts were integral. The shingles are thus made to 45 co-operate in resisting wind, rain, or storm, and the roof is a very permanent one, little liable to get out of order. Of course, like every other metallic roof, this should be well 50 painted to prevent oxidation.

I am aware that the grip-lock is not new, and that grooves have been used in sheet-metal shingles; but I know of none in which my long pitch-groove a, with all the branch grooves opening into it, has been employed; hence 55

What I claim, and desire to protect by Letters Patent, is—

A metallic shingle having the long groove a running from top to bottom with the pitch of the roof and all the oblique branches a' 60 opening thereinto, as shown and described.

GEORGE B. WEAST.
